mesne assignments, to the United States of
America as represented by the Secretary of
War

Application February 19, 1945, Serial No. 578,764

2 Claims. (Cl. 250—33.63)

1

The present invention relates generally to ultra-high-frequency antenna structures and more particularly to such structures of the biconical electromagnetic horn type adapted for use in connection with radar beacon stations.

In the horn radiator for ultra-high-frequencies, directivity is obtained by using a horn to guide and concentrate the radiated wave into a sharply defined pattern. Such radiators are capable of giving highly directional patterns when the mouth thereof has a dimension that is large relative to the wavelength. Horns become practical at ultra-high frequencies since then a dimension that is large compared with the wavelength does not entail excessive physical size. The field pattern obtained by exciting a horn radiator is determined by the shape and dimensions of the mouth measured in wavelengths and the variation in magnitude and phase of the field distribution produced across the mouth of the horn.

When a horn radiator is employed as a receiving antenna, the mouth gathers in a section of the passing wave. If this wave is travelling directly toward the mouth of the horn, then the horn in effect cuts out a slice of the wave having a cross section approximating that of the horn mouth. If the incoming wave approaches from an angle the effective cross section of mouth that this wave sees as it approaches the horn is reduced and the amount of energy that can be abstracted from the wave is likewise less. The end result is a directional pattern that is exactly the same as that obtained when the horn is used for transmitting.

In radar beacon stations, wherein an automatic-transmitter is operated by a radar signal transmitted by an aircraft to enable the aircraft to determine its azimuth and range with respect to the beacon, the antenna structure associated with the beacon is required to produce a radiation pattern which is uniform in all horizontal directions and which concentrates the energy outwardly permitting a minimum amount to be scattered into the ground and a small amount to be scattered vertically upwards since aircraft positioned vertically upwards will be at relatively short ranges and hence require less signal. The desired pattern should be fairly wide vertically, however, to obtain the desired coverage of the surrounding space.

The horn antenna most suited for beacon applications is that of the biconical type, consisting of a pair of conical conducting surfaces with common axis and oppositely disposed with nape

sections adjacent. When excited in a fundamental mode such a horn is characterized by a pancake type of radiation pattern in which the radiation is concentrated in a sharp beam in the vertical plane but is uniformly distributed in the horizontal plane.

Since a radar beacon must cover a large band width to accommodate all aircraft radar which might interrogate it, it is generally advantageous to have separate receiving and transmitting antennas. This is necessary in that a suitable duplexing device permitting the use of but a single antenna for transmitting and receiving is extremely difficult to realize in view of its limited band width, especially at microwaves.

Accordingly, it is the principal object of this invention to provide an antenna assembly for a beacon station comprising two sets of biconical antennas for transmitting and receiving.

Another object of this invention is to provide an assembly of the above-described type which is rigidly constructed and weatherproof.

Yet another object of this invention is to provide an antenna assembly of the above-described type incorporating radiators producing a pattern having horizontal polarization.

An additional object of this invention is to provide an antenna assembly of the above-described type incorporating radiators producing a pattern having vertical polarization.

For a further understanding of this invention, as well as other objects and features thereof, reference is made to the following description to be read in connection with the accompanying drawings wherein:

Figure 1 shows in vertical section a preferred embodiment of a biconical antenna assembly in accordance with the invention.

Figure 2 is an enlarged view of one of the radiating elements and the surrounding structure shown in Figure 1.

Figure 3 is a plan view of the radiating element shown in Figure 2 and,

Figure 4 illustrates a radiator adapted for vertical polarization.

Referring now to the drawings and more particularly to Figure 1, there is shown an antenna assembly comprising a biconical transmitting antenna 10 and a biconical receiving antenna 11.

Two sets of oppositely disposed conical reflecting surfaces are provided, the surfaces being indicated by numerals 12, 13, 14 and 15. The uppermost cone 15 and the lowermost cone 12 are axially apertured complementary to bush-

ings 29. These conical surfaces are mounted concentric with the vertical axis 16 and the remainder of the antenna assembly is symmetrical with respect to this axis. The lower pair of conical surfaces, 12 and 13, constitute a biconical horn which serves to concentrate to a certain degree the radiation from a radiating element 17 in a vertical plane and compels the radiation pattern to be horizontally symmetrical. Radiator 17 is connected through a coaxial transmission line 18 to the transmitter of the beacon.

The upper pair of conical surfaces 14 and 15 constitute a receiving horn having a directional pattern identical to that of the transmitting horn. The receiving antenna 19 is connected by means of a coaxial line 29 to the beacon receiver.

The entire assembly is vertically raised above ground and supported by means of an elevation pipe 21 concentric with coaxial line 18. Lateral movement of pipe 21 is prevented by means of ring clamps 36 connected to struts (not shown). A suitable covering sleeve 22, preferably composed of Plexiglas, completely envelops the assembly to provide weatherproofing therefor. The upper end of covering sleeve 22 is capped by a dome cover 23 which may be a cone similar to those used in the directive elements 12 and 15.

The rims or bases of reflecting surfaces 12 to 15 are flanged and bolted to the inner surface of sleeve 22. The construction details of the radiator 17, as well as the supporting structure connecting reflecting surfaces 12 and 13, may be more clearly viewed by referring to Figures 2 and 3. The construction details of receiving antenna 20 and the surrounding structure, being substantially identical with that of radiator 17, need not be shown.

To mount the conical surfaces rigidly and to maintain a fixed spacing therebetween, a collar 24 composed of non-conductive material is disposed between the napes of reflecting surfaces 12 and 13. The cones 12 and 13, the collar 24 and the discs 27 and 28 are provided with six circumferentially arranged, equally spaced, aligned bores to receive clamping bolts 25. Separating the transmitting antenna 19 from receiving antenna 20 is a separation pipe 26 bonded to an annular metal disc 27 bolted to the upper end of collar 24. The supporting pipe 21 is bonded to a similar disc 28 bolted to the lower end of collar 24 and the coaxial line 18 is maintained coaxially within pipe 21 by means of a metal bushing 29 secured to disc 28, the said bushing being fixed through the axial aperture in the cone 12.

Radiator 17 comprises three dipole radiating elements, each dipole having two circular segments, said segments being circumferentially arranged. The radiator is mounted equidistant from cones 12 and 13 and along axis 16. The dipoles are fed in a manner such that the current flows in the same angular direction in all elements. As is shown in Figure 3, in order to obtain the best condition of radiation impedance the bolts 25 are oriented with respect to the triple dipole radiation element 17 at evenly spaced positions.

Figure 4 illustrates means for constructing a unit of an antenna assembly producing a radiation pattern having vertical polarization. A biconical horn antenna is provided having two reflecting cones 30 and 31 identical in all respects with that shown in Figure 1. The radiating element herein is a section of a coaxial transmission line 32 whose outer conductor 33 is cut away over a short

length thereby exposing the central conductor 34. To match the radiation impedance of this element to the transmission line, a shorting plunger 35 is employed slidably received within the coaxial line 32 which may be adjusted in position to permit a maximum of radiated energy. In this case a bolting arrangement as shown in Figures 2 and 3 is no longer feasible since it would materially affect the radiation pattern produced, the bolts 25 being aligned in the polarization direction.

In Figure 1 the radiator 17 and receiving antenna 19 provide radiation patterns having horizontal polarization. The coaxial line 20 leading to the receiver may extend around and down parallel to the axis of the beacon antenna without destroying the radiation pattern. If the pattern is to be of vertical polarization as shown in Figure 4, the coaxial line connecting the receiving antenna may be concentric with the coaxial line connecting the transmitting antenna so that they may both extend along the axis 16 of the unit and form a coaxial line within a coaxial line. This arrangement being obvious is not shown. The spacing of the conical surfaces in a set is kept small so that the wave front of radiation does not produce destructive interference, in accordance with the principles underlying electromagnetic horn design.

While there have been described what are at present considered preferred embodiments of the invention, it will be obvious to those skilled in the art that various changes and modifications may be made therein without departing from the invention, and it is aimed in the appended claims to cover all such changes and modifications as fall within the true spirit and scope of the invention.

What is claimed is:

1. An assembly for a pair of biconical antennae comprising two sets of truncated, conical, reflecting surfaces oppositely disposed along a common axis, the said surfaces being flanged about their bases and provided with a plurality of circumferentially arranged, equally spaced, longitudinal bores about their truncated surfaces, the uppermost and the lowermost of said conical surfaces being axially apertured; a nonconductive spacing collar positioned between each set of conical surfaces along the axis thereof and provided with a plurality of equally spaced longitudinal bores; a circular, metallic, recessed disc positioned against the inner truncated surface of each of said conical surfaces and about the common axis thereof, the said discs being provided with a plurality of equally spaced bores, the bores in said surfaces, collars and discs being aligned to permit passage therethrough of conductive clamping bolts, the uppermost and the lowermost of said discs being axially apertured complementary to the apertured area of the conical surface adjacent thereto; an annular, metallic bushing having a downwardly extending axial portion adapted to be inserted through the apertured areas of said conical surfaces and discs, the said apertured conical surfaces and discs and the said bushings constituting extreme upper and lower antenna elements of said assembly; radiating elements positioned equidistant between each pair of reflecting surfaces, a pair of transmission lines fixed through the said bushings and connecting one of said radiating elements to a transmitter and the other of said radiating elements to a receiver; a rigid supporting member connected between the two antennae and fixed in the inter-

mediate recessed discs; a hollow second rigid supporting member coaxial with the lower of said transmission lines and fixed in the lower of said recessed discs; a waterproofing sleeve positioned about said antennae and fixed to the flanged bases of said conical surfaces; and a conical waterproofing cover having a downwardly extending flange and fixed about the upper portion of said sleeve, the said cap being centrally apertured to allow passage therethrough of the upper of said transmission lines.

2. An assembly for a pair of biconical antennae comprising two sets of truncated, conical, reflecting surfaces oppositely disposed along a common axis, the said surfaces being flanged about their bases and provided with a plurality of circumferentially arranged, equally spaced, longitudinal bores about their truncated surfaces, the uppermost and the lowermost of said conical surfaces being axially apertured; a nonconductive spacing collar positioned between each set of conical surfaces along the axis thereof and provided with a plurality of equally spaced longitudinal bores; a circular, metallic, recessed disc positioned against the inner truncated surface of each of said conical surfaces and about the common axis thereof, the said discs being provided with a plurality of equally spaced bores, the bores in said surfaces, collars and discs being aligned to permit passage therethrough of conductive clamping bolts, the uppermost and the lowermost of said discs being axially apertured complementary to the apertured area of the conical surface adjacent thereto; an annular, metallic bushing having a downwardly extending axial portion adapted to be inserted through the apertured areas of said conical surfaces and discs, the said apertured conical surfaces and discs and the said bushings constituting extreme upper and lower antenna elements of said assembly; a pair of coaxial transmission lines fixed through said bushings, one of said transmission lines being

connected to a transmitter and the other of said lines being connected to a receiver; a pair of three-element dipole radiators, each dipole having two circular elements circumferentially arranged, the said radiators terminating the said transmission lines and positioned equidistant between each pair of conical surfaces; a rigid supporting member connected between the two antennae and fixed in the intermediate recessed discs; a hollow second rigid supporting member coaxial with the lower of said transmission lines and fixed in the lower of said recessed discs; a waterproofing sleeve positioned about said antennae and fixed to the flanged bases of said conical surfaces; and a conical waterproofing cover having a downwardly extending flange and fixed about the upper portion of said sleeve, the said cap being centrally apertured to allow passage therethrough of the upper of said transmission lines.
